UNITED STATES PATENT OFFICE.

JERRY BARRY AND ELOGE DION, OF BLAINE LAKE, SASKATCHEWAN, CANADA.

APPARATUS FOR REFRIGERATION.

1,262,161.

Specification of Letters Patent.

Patented Apr. 9, 1918.

Application filed October 12, 1916. Serial No. 125,285.

To all whom it may concern:

Be it known that we, JERRY BARRY and ELOGE DION, a citizen of the United States and a subject of the King of Great Britain, respectively, residing at Blaine Lake, in the Province of Saskatchewan and Dominion of Canada, have invented new and useful Improvements in Apparatus for Refrigeration, of which the following is a specification.

This invention has relation to refrigerators and has for its object to provide a refrigerator wherein the refrigerant employed is finely divided ice mixed with a suitable proportion of a saline substance having the property of further reducing the temperature of the mixture, whereby a lower temperature may be secured in the refrigerator than would be possible by the use of ice alone, and whereby the low temperature of the refrigerator may be maintained for a longer period for the same quantity of ice employed, than in refrigerators of the types heretofore provided.

Another object of the invention is to provide an apparatus wherein a region of extremely low temperature is maintained, below the freezing point of water for instance, and a second region of refrigeration designed to be maintained at a higher temperature than the colder region for the preservation of food stuffs, the temperature of the warmer region to be maintained by the regulated admission of air from the colder region as required.

A still further object of the invention is to provide a refrigerator embodying the principle of refrigeration as set forth above with a novel arrangement of cooling chambers, air passages and drains, whereby the highest possible cooling efficiency per unit quantity of refrigerant employed can be effected.

In addition to the foregoing, our invention comprehends improvements in the details of construction and arrangement of parts to be hereinafter more fully described and particularly set forth in the appended claims.

In the accompanying drawings in which similar and corresponding parts are desig-

nated by the same characters of reference throughout the several views in which they appear:

Figure 1, is a vertical longitudinal section taken through a refrigerator embodying the principle of the present invention, and

Fig. 2, is a vertical transverse section taken on the line 2—2 thereof.

Fig. 3 is a fragmentary sectional view showing the air conduit.

With reference to the drawings, 1 and 2 indicate respectively the front and rear walls of a refrigerator, 3, the end walls, and 4 and 5 respectively the bottom and top walls. 6 Each wall is formed of an inner panel section 6 and outer section 7 in spaced relation, with the space therebetween filled with a suitable heat insulating material 8, such as saw dust, magnesia, etc. The refrigerator 70 is provided interiorly with a vertical partition 9, formed in a manner similar to the walls, of spaced panel sections filled with heat insulating material. In this manner, two chambers are provided, indicated at 10 75 and 11, communication between said chambers being established through the agency of openings 12 and 13 extending transversely through the partition 9, and located at the lower and upper portions thereof as indicated in the drawing.

The chamber 11, which for the sake of convenience may be termed the freezing chamber, is provided with refrigerant tanks 14, spaced longitudinally as indicated in Fig. 1, each tank extending from the front to the rear of the chamber and provided at their top portions with filling hoppers 15 normally closed by plugs or the like 16. The refrigerant tanks may, in addition to their primary function, serve to support the ends of horizontal shelves 17 upon which articles may be supported. The tanks are further connected by means of a pipe 18, having communication at either end with the interior of the tanks at a point slightly above the bottoms thereof, one of the tanks being further provided with a drain pipe 19 connected thereto at a vertical distance from the bottom thereof in a manner similar to the connecting pipe 18, the drain pipe 19 preferably extending through the cham-

ber 10 to a point exteriorly of the refrigerator. The chamber 10 may also be provided with a number of shelves 20 to support articles and this chamber, for the sake of convenience, may be termed the refrigerating chamber.

The present invention further contemplates the provision of means for permitting the entrance of air from the outside where-
10 by circulation interiorly of the refrigerator may be promoted, and to that end the front wall is formed with a vertical conduit 21 by providing vertical partitions 22 between the inner and outer panel sections, the lower end of the conduit being in communication with the atmosphere at its lower end as indicated at 23. The upper end of the conduit is in communication with a horizontal channel 24 formed within the top wall 5 of the
15 refrigerator, said horizontal channel having communication with a transversely extending channel 25 which opens at its opposite end into the upper portion of the chamber 11, as indicated in Fig. 2.

20 Access to either chamber may be had through the agency of doors 26 constructed of spaced panel sections filled with heat insulating material in a manner similar to the walls of the refrigerator.

25 In use, each tank 14 is filled with a mixture of shaved ice and salt, in suitable proportions, through the filling hoppers 15, and the plugs 16 replaced. This mixture, especially when the ice is finely divided, has the
30 effect to quickly reduce the temperature within the chamber 11 to 32° F. or below, depending upon the proportion of tank surface to the volume of the chamber. Articles of food placed upon the shelves within the
35 chamber will, in due course become frozen, and in this condition will remain wholesome for an indefinite period.

40 In the case of food stuffs, required for immediate consumption or dispensing, and
45 which must be retained at a low temperature but not frozen, are kept in the chamber 10, the temperature is maintained by removing the plugs from the openings 12 and 13 to permit circulation of cold air from the chamber 11, the air taking a course through the openings 12, through the chamber 10 in an upward direction through the opening 13, and into the chamber 11 in a downward direction, the air being thus
50 cooled after having abstracted heat from the articles in the chamber 10.

55 If the openings 12 and 13 are permitted to remain open, the chamber 10 will obviously be reduced to the temperature of the chamber 11. This however is not desirable, and when the air in the chamber 10 has been reduced to a temperature of 35° F. or less which temperature will be sufficient to preserve articles of food, the openings 12 and
60 13 are again plugged, or one of the openings
65

at the upper and lower end of the partition may be left open sufficient to permit the maintenance of a refrigerating temperature without freezing the articles. The relative temperatures of the freezing and preserving 70 chambers may be determined by extending thermometers thereinto and the temperature of the preserving chamber may be thus maintained in a more positive manner.

The refrigerator described above embodies 75 as before stated, a freezing and preserving chamber with means for regulating communication therebetween, but it will be obvious that the principle of the present invention may be embodied in a refrigerator 80 consisting of but a single chamber with one or more refrigerating tanks placed therein. The design of the refrigerator may be further varied from that herein illustrated by disposing the chambers in superposed relation with the refrigerating tank in the upper chamber. Thus, the design of the refrigerator, the relation of the chambers, etc., may be varied to suit the requirements of the purpose to which the refrigerator is designed to 90 be put. Refrigerating cars, industrial refrigerators, etc., as well as smaller refrigerators for household use may be constructed embodying the principles hereinbefore given without departing from the spirit of the invention. 95

Therefore, while we have illustrated and described our invention with some degree of particularity, we realize that in practice various alterations may be made, and we 100 therefore reserve the right and privilege of changing the form of the details of construction, or otherwise altering the arrangement of the correlated parts without departing from the spirit of the invention or 105 the scope of the appended claims.

Having thus described our invention what we claim as new and desire to secure by Letters Patent is:—

1. In a refrigerator, a partition defining 110 freezing and refrigerating chambers, refrigerating means in the freezing chamber including a plurality of tanks adapted to contain a mixture of finely divided ice and salt, drain pipes for said tanks extending 115 therefrom at points vertically spaced from the bottoms thereof to the exterior of the refrigerator, an air conduit extending from the atmosphere to the upper portion of the freezing chamber, and means for regulating 120 circulation of air from one chamber to another whereby the temperature of the refrigerating chamber may be maintained at a higher degree than the freezing chamber.

2. In a refrigerator, having heat insulated 125 walls, a heat insulated partition therein defining freezing and refrigerating chambers, said partition having transverse openings therethrough at the top and bottom portion thereof, plugs for controlling the circulation 130

of air through said openings from one chamber to another, the walls of the refrigerator having an air conduit formed therein extending from the atmosphere to the upper portion of the freezing chamber, and refrigerating means comprising longitudinally spaced tanks depending in the freezing chamber having filling openings whereby the tanks may be filled with a mixture of finely divided ice and salt, shelves supported between and upon the tanks, and drain pipes extended

from the tanks at points vertically spaced from the bottoms thereof.

In testimony whereof, we affix our signatures in the presence of three witnesses.

JERRY BARRY.
ELOGE DION.
